United States Patent Office.

HENRY J. WILLING, OF CHICAGO, ILLINOIS, ASSIGNOR TO MARSHALL FIELD AND LEVI Z. LEITER, OF SAME PLACE.

Design No. 3,506, dated May 18, 1869.

DESIGN FOR A TRADE-MARK.

The Schedule referred to in these Letters Patent and making part of the same.

To all whom it may concern:

Be it known that I, HENRY J. WILLING, of the city of Chicago, in the county of Cook, and State of Illinois, have originated a Design for a Trade-Mark, of which the following is a full, clear, and exact description, reference being had to the accompanying drawings, making part of this specification.

A represents a chevron-escutcheon, having two sheaves of wheat above and one sheaf of wheat below the rafter.

B represents a garter, encircling the escutcheon.

On it are printed the words, "American Hosiery Co."

C represents a crown, which surmounts the whole.

What I claim as my invention, and desire to secure by Letters Patent, is—

The design for a trade-mark, herein set forth and shown.

H. J. WILLING.
